UNITED STATES PATENT OFFICE

160,284

COMBINED COASTER AND ASH TRAY OR
SIMILAR ARTICLE

Leila G. Strong, Detroit, Mich.

Application February 24, 1950, Serial No. 8,094

Term of patent 14 years

(Cl. D44—10)

To all whom it may concern:

Be it known that I, Leila G. Strong, a citizen of the United States and a resident of the city of Detroit, in the county of Wayne and State of Michigan, have invented a new, original, and ornamental Design for a Combined Coaster and Ash Tray or Similar Article, of which the following is a specification, reference being had to the accompanying drawing, forming a part thereof.

On the drawing:

Figure 1 is a plan view of a combined coaster and ash tray, showing my new design; and

Figures 2 and 3 are, respectively, front and rear elevational views thereof.

I claim:

The ornamental design for a combined coaster and ash tray or similar article, substantially as shown.

LEILA G. STRONG.
